 corporation of New York

Application March 17, 1945, Serial No. 583,370

4 Claims. (Cl. 220—4)

1

This invention relates to cabinet structures and particularly to such structures which have a wide range of use and enhance accessibility. Cabinets of the type herein disclosed, or combinations of the same, are commonly employed in kitchens, pantries, bath rooms, restaurants, hospitals, stores and, in fact, anywhere where the neat and readily accessible storage of commodities or implements is desired. The instant invention deals principally with the structure of a cabinet per se while at the same time bringing out the adaptability of my type of cylindrical cabinet to combinations building up to a complete kitchen, pantry, or other combination.

Moreover, certain of the basic features of my cabinet are applicable equally as well to such constructions as refrigerators, stoves, broilers, and instrument cabinets, as they are to a common storage cabinet, hence the term "cabinet" when and as used herein is to be understood as used in an illustrative rather than a limiting sense.

Cabinets as previously employed had many drawbacks. In the first place it was the common practice to make most of them either square or rectangular, because it was believed that greater storage space was thus obtained and because such cabinets fitted the space normally available for them. In order to increase their capacities, however, they were often made of such a depth that it was practically impossible to get at things stored in the back part of them, or on the back part of their shelves, without removing everything in the front. The back space was thus of little value and was usually not used at all.

The hinged doors of prior art cabinets were both a nuisance and a hazard. They projected out into the room when open and had to be closed after each opening to avoid one's bumping into them and injuring oneself, or even to use the space that they occupied when open. Rarely, if at all, were stoves or refrigerators supplied in shape or size so related to the rest of the cabinets that all could be fitted in together to make a complete kitchen out of harmonious units of elements.

In the few instances in the past where cabinets with cylindrical exteriors were employed, they were usually awkward, were permanently fixed in place and precluded any modification without rebuilding. The prior art mounting of cylindrical shelves was usually complicated, expensive and space-consuming, with a center pole or pivot being commonly employed as the mount-

2

ing means. Finally, no one had the vision to conceive of a whole kitchen or pantry made up of interchangeable cylindrical elements. Rather the prior practice called possibly for one cylindrical cabinet amongst a number of rectangular ones where it was obviously out of place.

In addition to curing the defects of the prior art constructions, the cabinets of my invention go several steps forward in cabinet development.

- 10 In the first place, all of the elements of the same size, whether stove, refrigerator or mere storage cabinet, are interchangeable with one another. All normal types of cabinets made in accordance with my invention, can be used with either end up.
- 15 This is particularly advantageous when right-hand as against left-hand doors are desired. Furthermore, a cabinet of one height may be replaced by a series of cabinets of lesser height whose total height equals that of the original cabinet. This, 20 where kitchens are concerned, enables the building up of complete kitchens to suit the tastes of the users thereof as to position, capacity and convenience of the various elements such as ordinary storage cabinets, refrigerators, stoves and broilers. When the desired elements are all selected, the complete kitchen is mounted on its own supports which are independent of the wall of the building and can thus be easily installed, removed, or changed. Most of the details of such installation form no part of the instant application.

The independent cabinets of my invention, as already mentioned, are as readily useable with one end up as with the other. In accomplishing this, 35 I have reduced the number of parts to a minimum and simplified the construction by making parts of each cabinet interchangeable with other parts of the same cabinet. The doors of my cabinets are cylindrical and turn inside the main cabinet wall to open, so that they are out of the way. The shelves are interchangeable and the intermediate shelf or shelves are adjustably and pivotally mounted by easily operable unobtrusive means.

It is accordingly an object of my invention to 40 provide cylindrical cabinet constructions of wide applicability.

It is another object of my invention to provide such cabinets which are readily interchangeable, one with another, and can be readily combined, 50 one with another to form combinations of various heights and sizes.

It is another object of my invention to provide such cabinets whose storage space and accessibility are kept at a maximum.

55 Still another object of my invention is to pro-

vide such cabinets which are useable either end up and are fully interchangeable, regardless of which end is up.

A further object of my invention is to provide such cabinets whose construction is simple, economical and foolproof.

A still further object of my invention is to provide such cabinets with interior elements which are adjustable and useable with equal facility, no matter which end of the cabinet is up.

A still further object of my invention is to provide such cabinets so constructed that the parts and assembly thereof can be formed and performed by simple operations employing unskilled labor.

Other and further objects of my invention will become apparent as the description of the invention proceeds and by reference to the accompanying drawings in which:

Figure 1 is an elevation showing one manner in which the cabinet units of my invention may be assembled to form a complete kitchen;

Figure 2 is a schematic section taken on lines 2—2 of Figure 1;

Figure 3 is a perspective view of a cabinet unit in accordance with my invention, showing the door of the cabinet part way open;

Figure 4 is a plan view of the cabinet of Figure 3;

Figure 5 is an enlarged sectional view taken on lines 5—5 of Figure 3 showing the detail of the interior of the cabinet;

Figure 6 is an enlarged fragmentary perspective showing the shelf mounting member of my invention and the manner in which the same is supported on a wall of the cabinet;

Figure 7 is a fragmentary elevation partly in section showing the manner in which a shelf is mounted within the cabinet;

Figure 8 is a perspective view of the shelf mounting member;

Figure 9 is a fragmentary section taken on lines 9—9 of Figure 8;

Figure 10 is a fragmentary sectional view of one end of a cabinet showing the construction thereof, and the door and end shelf mounting therein;

Figure 11 is an enlarged fragmentary elevation in section, showing the interengagement of the side and end walls of the cabinet;

Figure 12 is a view similar to Figure 10, but showing a cabinet with the other end up;

Figure 13 is a fragmentary perspective view of a portion of the rotating door and the means for mounting the same;

Figure 14 is a fragmentary horizontal section showing the construction of the cabinet at one side of the opening therein, the manner in which the door is stopped at that side, and the means for engaging the cabinet with an adjacent cabinet;

Figure 15 is a fragmentary horizontal section, showing the construction of the cabinet at the other side of the opening therein;

Figure 16 is a fragmentary elevation of the door showing the finger-grip embossing therein;

Figure 17 is a fragmentary vertical section of the cabinet wall taken at a position adjacent to the left-hand side of the opening therein, as viewed in Figure 3;

Figure 18 is a fragmentary vertical section of the cabinet wall taken at a position adjacent to the right-hand side of the opening therein, as viewed in Figure 3;

Figure 19 is a fragmentary vertical section of

the cabinet wall with the stiffener member carrying the center shelf mounting member supporting lugs thereon;

Figure 20 is a fragmentary vertical section of the cabinet wall showing the stiffener member carrying the left-hand shelf mounting member supporting lugs as viewed in Figure 5;

Figure 21 is a section on lines 21—21 of Figure 17;

Figure 22 is a section on lines 22—22 of Figure 18;

Figure 23 is a section on lines 23—23 of Figure 19; and

Figure 24 is a section on lines 24—24 of Figure 20.

It will be noted from a study of the accompanying drawings that in some of the views no attempt has been made to include all of the detail which might have been shown by dotted lines and the like. Such detail is, however, shown independently and in enlarged views as well as in views which show sufficient of each portion of an individual cabinet to show how the detail fits into the construction of the cabinet as a whole. It is believed that this manner of presentation will expedite a study of the drawings and the understanding of the invention.

Figures 1 and 2 are included principally to furnish background and to give one example of the combinations to which the cabinet units of my invention may be put. No attempt has been made to go into precise detail in these figures. Their purpose is merely to illustrate generally how such as a complete pantry or kitchen installed in a room would look were all of the cabinet units employed made in accordance with this invention. The manner in which the cabinet units are assembled into vertical sections forming groups of cabinets or into an assembly comprising combinations of such sections and the manner in which such an assembly is removable mounted in place within a room without being physically attached to the walls of such room, involve inventions in and of themselves. It is not the province of this application to treat with such inventions, so that the detail of them is omitted herefrom.

In the Figure 1 showing, I have illustrated the combining of larger lower cabinets, such as 5 and 6, with shorter cabinets such as 7 and 8 to make a section of the same height as achieved by putting together two intermediate length cabinets, 9 and 10. Further, it is to be noted that the doors of the cabinets 5 and 7, as indicated by the finger grips thereof 11, operate in reverse direction to those shown in Figures 6 and 8. In similar manner, various combinations of smaller upper cabinets such as 12, 13, 14 and 15 can be combined and arranged to provide any suitable combination.

Extra large end cabinets such as shown at 16, 17 and 18 may similarly be combined or reversed as desired. As an alternative, one of these ends could be made as a single cabinet extending throughout the full height of the section. Such cabinets are commonly employed for the storage of long, unwieldy articles such as vacuum cleaners, carpet sweepers, brooms and the like. Finally, Figure 1 also shows perforated kick plates such as 19 and 20, on which the cabinets are mounted. The particular structure and purpose of these is treated elsewhere.

In Figure 2, I have shown somewhat schematically the manner of tying the cabinets together and mounting them in a room without making

them a part of that room. Generally speaking the cabinet units are mounted on, and supported by a frame work, free from the wall, consisting of vertical members. Here again it is not the province of this application to treat with the details of this construction. The purpose of these showings is to illustrate how simply and effectively cylindrical cabinet units, as hereinafter described, can be employed and combined.

In Figure 2 there is also illustrated the work tops, such as 23 and 24, employed over my larger lower cabinets. Finally, I have shown in Figure 2 the manner of finishing off the whole construction to blend into a room. This is done by the use of end pieces 25 extending from the end cabinets and scribed to the wall. These are about the only elements of the whole construction which must be made to conform to the walls of the room.

To illustrate the structure of a specific cabinet, which structure is the essence of this invention, I have selected one of the more simple forms employed, but one which incorporates all the basic elements of my invention. Such a cabinet is that shown at 9 in Figure 1 and in the perspective view of Figure 3. Not all the details of the cabinet unit appear in Figure 3, but those which do not are more fully developed in the subsequent views.

Cabinet units made in accordance with my invention will preferably be made of metal, as it can be readily worked into the forms desired. Other materials may, of course, be employed where suitable, so I do not wish to be limited to metal for the construction of all or any particular part of my cabinet.

Considering first the side and end walls of the cabinet unit and the manner in which they are interengaged, the vertical side wall 26 forms a substantial portion of a cylinder, leaving out of course a section providing for the opening into the cabinet. The wall 26 thus terminates in the spaced-apart sides 27 and 28 of the wall opening. The ends of the wall are in planes at right angles to axis of the cylinder. Being both the same, these ends are readily receivable by identical end members 29 and 30. The employment of identical end members not only saves labor and materially simplifies the assembly of the cabinets but this is one feature which assists materially in enabling the cabinets to be used with either end up.

The end members 29 and 30 being identical, only one need be described. Generally they are in the form of a disc-like base portion 31 provided around its periphery with an offset embossed channel 32, shown best in Figure 11, which channel is generally U-shaped in cross section. The bottom portion 33 of the channel 32 is of substantial width and is generally parallel with the base portion 31. From the bottom 33, the wall of the embossing turns directly upward to form the engaging wall 34. This wall extends at right angles to the base portion 31 back to the plane of the same and terminates in an out-turned bead portion 35. Thus as clearly seen in Figure 11, when the side wall 26 is engaged with an end member, the portion 36 of the wall 26, adjacent the free end thereof, is supported by the wall 34 and is received in the turned-over bead or lip 35.

The base portion 31, as shown in Figures 10 and 12, has a hole punched in its center at 37 and is embossed inwardly therearound, at 38, to form a shallow depression. The embossing 38 receives a fitting 39 whose base is received in the embossing and is held in place therein by means such as the screws shown. The fitting 39 has a center hub

40 which extends through the opening 37, and thus into the interior of the cabinet when the same is assembled. This center hub is bored internally as shown at 41 to provide for the pivotal mounting of a shelf as described hereinafter. In addition, the outside of the hub 40 is formed with a surface 42 for the pivotal mounting of one of the door supports thereon, about also to be described.

Considering next the door 43 for closing the opening in the cabinet, it is to be noted that the same is also formed as a portion of a cylinder. This cylinder, however, is of a shorter radius than that of the outside of the cabinet and (as seen from Figures 10 and 11) than that of the embossing 32 around the end members. Thus the door is free to swing from open to closed position within the cabinet.

I have found that a simple and effective construction for the door is to form the same out of spaced concentric sections, 44 and 45, of lightweight material. These sections 44 and 45 are kept spaced apart but secured together by means of flanging the side edges of each section in opposed directions and overlapping such flanges as shown at 46-47 and 48-49. Screws are then passed through the flanged portions as shown in Figures 14 and 15. The flanging at 48, however, as best shown in Figure 14, is first bent downwardly with respect to the sheet 44 before it is turned back inwardly to form the portion 48. This outwardly turned portion 50 serves as one part of a stop and closing construction to limit the movement of the door in one direction and to close what might otherwise be a vertical opening at that point.

The door is pivotally mounted and additionally supported by means of identical sets of radial arms 51, 52 and 53 which converge inwardly to terminate in a pivotal portion 54 formed with an internal pivotal surface 55. This surface 55 engages with and pivots about the surface 42 formed on the fitting 39, as already described. The arms 51, 52 and 53 are anchored to the door member and assist in supporting the same by having their ends turned at right angles to the body portions thereof and extended for a short distance inwardly between the sections 44 and 45, as shown at 56 in Figures 10 and 12. In addition, the exterior arms 51 and 53 which meet the door just within the flanged over edges thereof are interengaged by the same screws which are employed to hold together the flanged over ends 46 with 47 and 48 with 49. It is of course to be understood that the pivotal mounting and support for the ends of the door are identical so that the same construction can be used at either end.

As a means for operating the door, I have found that all that is necessary is a depression or finger hole such as that shown at 57 in Figure 16. It is merely an embossing in the outer sheet and the use of any additional element is thus obviated. Furthermore, I have also found that no latch or catch mechanism is necessary to hold doors of this type in closed position, for they stay where they are put. Since these doors operate around inside of the cabinet, they are never in the way. The housewife may open the door to a cabinet when she commences to get a meal and leave it open until the meal is completed and everything cleared away, leaving the closing of the cabinet doors as the last step in the clearing up operation.

Though the instant cabinet is shown as one having merely two shelves, one at the bottom of the cabinet and another one which is mounted

intermediate the ends thereof, it is of course to be understood that the number of intermediate shelves to be employed would be a matter of convenience and would be principally determined by the height of the particular cabinet. The end shelf as shown in Figure 10, which would of course be used at whichever end happened to be the bottom at the time, and the intermediate shelf as such, shown in Figure 7, are of identical construction. They are in the form of a shallow circular tray 57 having an upwardly extending lip 58 therearound. Their maximum diameter is such that when mounted centrally of the cabinet they will, as shown in Figure 5, be free to turn just inside the inner section 45 of the door 43.

The tray 57 is secured to a supporting member such as the spider 59, which terminates in a central hub 60 for the pivotal mounting of the tray in the bearing provided therefor. The hub 60 is also furnished with a laterally extending surface 61 designed to engage the upper surface of the mounting member to steady the shelf. The mounting of the shelf at the bottom of the cabinet, is readily accomplished as shown in Figure 10, by inserting the hub 60 into the pivotal recess 41 which is designed to receive it. Merely placing it there is sufficient, as would also be true were it to be engaged in the like mounting at the opposite end of the cabinet, assuming the cabinet to be the other way up. The hub 60 is similarly receivable in the pivotal mounting of the mounting member for the intermediate shelf or shelves to be described hereinafter. Here also, provision is made for additional steadyng of the shelf by providing a receiving surface for the surface 61.

In order to stiffen the cylindrical wall 26 and to take care of several other requirements, the cabinet is provided with vertically extending stiffener members 62, 63, 64 and 65 shown in detail in Figures 17 to 24. Considering, first, stiffener member 62, which is located at the left side of the cabinet opening as viewed in Figure 3, it is seen that the same is a bar of material somewhat heavier than the wall of the cabinet. This bar lies against the outside of the wall 26, extends throughout substantially the entire height thereof and terminates just within the beads 35 formed on the end members of the cabinet. The stiffener 62 has a pair of identical lugs 66 extending laterally from the inner surface thereof. These lugs, 66, are appropriately spaced from the ends of the member 62, so that when that member is brought up against the side wall 26 with the lugs 66 extended through apertures in that wall, they will underlie the bottoms 33 of the annular embossings 32 around the bases 31 of the end members. The lugs 66 are provided with screw threaded bores to receive screws 67 passed through registering holes in the portion 33. Obviously this construction serves to stiffen and strengthen the side walls of the cabinet and at the same time positively secures the ends of the cabinets in interengagement with the sides thereof. Additional stiffener members 63, 64 and 65 are similarly provided with lugs 66 identical with the lugs 66 of member 62 and which similarly receive screws 67 to assist in holding the ends and side walls of the cabinets in assembled relation as well as strengthening the side walls.

As already pointed out, stiffener member 62 lies against the outside of the side wall 26 of the cabinet. At the same position another member is secured against the inside of the cabinet wall and is secured to both the cabinet wall and the stiffener member 62 by some suitable means such

as a rivet. This member has a base portion 68 lying against the inner face of the wall 26 and a stop portion 69 extending inward from the wall 26 at right angles thereto. From the innermost extremity of the stop portion 69 this member extends in a reversely bent part 70 to a position outside of the cabinet, where it terminates in a back-turned securing lip 71. The securing lip 71 is designed to be adjacent to a comparable member on the next cabinet and be engaged by means employed to join the cabinets together. This joining feature is not gone into further in this application. The member 68-69-70-71 extends throughout the full height of the cabinet as shown in Figure 3. Other important functions that it performs are in its part 69 acting as a stop for engagement with the stop shoulder 50 formed on the door to limit the movement of the door in closing direction and also as a seal to close the crank which might otherwise appear between the outer surface of the door and inner surface of the wall.

The other side of the opening is similarly provided with a stop and securing member having a portion 72 secured to the inside of the wall 26 at the position where that wall is supported on its exterior by the stiffener 63. Here the right angle internally extending abutment member 73 extends further inward of the cabinet than does the stop member 69. The portion 73 is also reversely bent and folded against itself for a distance equal substantially to the width of the door. This folded portion serves as an abutment for the leading edge of the door to stop it when it reaches fully closed position and to form, with the edge of the door, a seal to provide a complete closure. From the reversely folded portion 73 the member extends outwardly of the cabinet wall to form portions 70 and 71, identical with the portions 70 and 71 previously described. Before leaving this feature, it is to be noted that the backwardly extending portion 71 lies substantially on a tangent to the horizontal diameter of the cabinet as viewed in the Figure 4 or 5 positions. Thus the portion 71 is readily available for the joining of its cabinet to an adjacent one.

Another important feature of my invention is noted from the showing in Figures 6, 18, 19 and 20. Here the stiffener members 63, 64 and 65 are seen to be equipped with additional sets of lugs extending through the wall of the cabinet and for a short distance within the same. The stiffeners 63 and 65 each present a series of four evenly spaced lugs to which the reference characters 74, 75, 76 and 77 are applied in each instance inasmuch as they are identical and are similarly located with respect to the vertical extent of the stiffener members. These lugs serve as engaging means for the transverse arm of a cantilever member, about to be described, which is employed for the mounting of the intermediate shelf. They cooperate with a set of three lugs 78, 79 and 80 extending from the spacer member 64, which lugs are designed to engage the center portion of the cantilever member referred to. It is to be noted that each of the lugs 78, 79 and 80 is positioned intermediate of a pair of the lugs 74, 75, 76 and 77. The purpose of such positioning will appear presently.

The cantilever shelf mounting member, shown by itself in Figure 8, and in mounted positions in Figures 5, 6 and 7, has a center member 81 whose

inner end is provided with a pivotal mounting 82 to receive the hub 60 of a rotatable shelf member as already described. The outer end of portion 81 is provided with an upwardly extending pin 83, and, just a little inward from the pin 83, the member 81 is also provided with laterally extending arms 84 and 85. These arms have their end surfaces 86 and 87 formed to the contour of the inside of the wall 26. The pin 83 is of a size to be accommodated by vertical bores 88, 89 and 90 formed in and extending through the three lugs 78, 79 and 80.

It is believed that from the showing in Figures 5, 6 and 7, it will be apparent how the cantilever shelf mounting member 81 is employed. Obviously, the arms 84 and 85 will have to be supported from beneath by corresponding pairs of the lugs 74, 75, 76 or 77, while the pin 83 will have to be inserted into one of the openings 88, 89 or 90, with the upper face of the member 81 around the pin 83 being engaged underneath the appropriate one of the lugs 78, 79 or 80. The purpose of the three lugs on the member 64, and the four equally spaced and similarly located lugs on the members 63 and 65 is to allow an adjustment of the shelf mounting member to any one of three different positions, regardless of which end of the cabinet is up. Assuming then that it is desired to install or adjust the position of the intermediate shelf, all that need be done is grasp the cantilever member 81 and slightly raise its end 82 while at the same time bringing the ends 86 and 87 of its cross member down on top of a pair of lugs, such as 75, on the members 63 and 65 respectively. Inasmuch as the end 82 is tilted upwards the end carrying the pin 83 is thus below its normal level, and the pin 83 will thus pass beneath the lug 78. A rocking of the end 82 downward will seat the pin 83 in a bore 88 and enable the surface of member 81 around the pin 83 to engage the under side of the lug 78 at which time the shelf support will be in horizontal position. To remove member 81 and adjust the shelf to a different position, it is merely necessary to tilt the end 82 upward and repeat the process, engaging the ends 86 and 87 and the pin 83 with whatever related lugs are selected. Obviously this mounting, removal and adjusting of the cantilever shelf mounting member 81 can be accomplished with equal facility regardless of which end of the cabinet is up. It is not even necessary to remove the shelf from the mounting 82 in order to do this, but the housewife or other user of the cabinet would probably find it easier to manipulate the shelf mounting member without the shelf in place. Though I have shown one specific form of cantilever member, it is of course obvious that such member can be formed in different ways and still embody the principle underlying this feature of my invention. Before leaving the discussion of this feature of my invention, it is to be particularly noted that my cantilever shelf mounting construction, though providing ample strength for the support of articles placed on the shelf, and providing an entirely adequate mounting for a detachable, rotatable shelf nevertheless reduces to the barest minimum the amount of storage space in the cabinet taken up by it. Furthermore, the construction of the mounting member of the lugs for supporting it and of the shelf itself, are extremely simple in construction, as well as in operation. They are accordingly economical to

make and lend themselves to every-day use without introducing any handling complications.

Another function performed by the stiffener member 63 and its lugs 74 to 77 is to act as a stop for the door 43 when the same is opened as far as it is intended it should go. The member 63 is so positioned that the stop action comes into play just as the finger grip 11 arrives at the member 10. At this point the end 48 of the door abuts against the lugs 74 to 77. Thus a proper positioning of an existing member is all that is needed to assure the performance of a function which would normally call for the use of an additional member.

From the foregoing it will be readily apparent that I have devised a cylindrical cabinet unit so complete yet so simple and economical that it goes far in advance of any cabinet constructions, whether cylindrical or not, heretofore contemplated. Furthermore, and somewhat in spite of its extreme simplicity and economy, my cabinet member not only lends itself admirably to combination with or interchange with counterparts of varying sizes, but also combines admirably into vertical sections of similar cabinet units and assemblies consisting of several of such vertical sections.

While, as already pointed out, my invention has been considered from the point of view of its use in a kitchen or as part of a complete kitchen, and also has been considered as an ordinary storage cabinet, it is of course to be understood that such has been done merely for the sake of convenience of illustration. The cabinet is useable in many situations and locations other than kitchens, and the basic features of its construction are readily adaptable to other fields such as, but without limitation to, refrigerators, stoves and broilers. Other changes and modifications which could be made without departing from the spirit of my invention will become apparent to those skilled in the art, and I therefore desire that only such limitations shall be placed upon my invention as are found in the appended claims.

45 What I claim is:

1. A cabinet comprising a continuous vertical wall portion forming a portion of a cylinder but terminating in spaced vertical free edges to form an opening, identical end members closing the ends of said cylindrical portion, stiffener members extending throughout the height of the side wall of said cabinet, lying against one side of said wall and formed with inwardly extending lugs adjacent the ends thereof, said lugs extending through from one side to the other of said side wall, and means for engaging said lugs with said end members, said engaging means serving to hold said stiffener member to said side wall and secure said side wall and end members together.

60 2. In cabinet construction, a side wall comprising a continuous thin metallic member forming a substantial portion of a cylinder, the vertical free edges of said member being spaced apart to provide access to the interior of said cylinder portion, identical end members engaging the ends of said cylinder portion and closing the same, a strap-like supporting member engaged with the outer surface of said cylinder portion and extending substantially throughout the height of the same, laterally extending lugs formed integrally with said supporting member and extending from one face thereof at spaced positions throughout the height thereof, said cylinder portion being formed with perforations

11

for the reception of said lugs and said lugs inserted in said perforations with portions of said lugs extending inward beyond the inner surface of said cylinder portion, the inner portions of two of said lugs lying closely adjacent portions of said end members, and means for securing said inner portions of said lugs and said end members together whereby said supporting member serves to support said cylinder portion and to secure said cylinder portion and said end members in assembled relation.

3. In cabinet construction as defined in claim 2, said supporting member being provided with an additional lug spaced from the ends of said supporting member, said additional lug extending into the interior of said cylinder portion for supporting an element within said cylinder portion.

4. A cabinet comprising a continuous vertical side wall portion formed of thin sheet material, said side wall portion forming a portion of a cylinder, said cylinder portion terminating in spaced vertical free edges to form an opening, end members closing the ends of said cylinder portion and a strap-like re-enforcing member engaged with the outer surface of said side wall portion and extending throughout the height of the same from one end member to the other, said re-enforcing strap being formed with laterally off-

10

12

set portions at spaced positions along the length thereof, and said wall portions being formed with perforations therein in registry with said offset portions of said re-enforcing strap whereby said re-enforcing strap serves to provide a shelf support engaging member at spaced vertical positions within said side wall portion.
